DESIGN FOR A SLIP

Julia Lutfy Sarge, New York, N. Y.

Application March 30, 1937, Serial No. 68,476

Term of patent 3½ years

To all whom it may concern:

Be it known that I, Julia Lutfy Sarge, a citizen of the United States of America, residing in Manhattan, county of New York, and State of New York, have invented a new, original, and ornamental Design for a Slip, of which the following is a specification, reference being had to the accompanying drawing, forming part thereof, wherein,

Figure 1 is a front view of a slip showing my new design.

Figure 2 is a rear view of the slip shown in Figure 1.

Figure 3 is an enlarged fragmentary view of a row of the shell-tucking appearing on the slip, as shown.

I claim:

The ornamental design for a slip, substantially as shown and described.

JULIA LUTFY SARGE.
